CHEMICAL PROCESS

Walter F. Rollman, Cranford, N. J., assignor, by
mesne assignments, to Jasco, Incorporated, a
corporation of Louisiana

Application November 15, 1941, Serial No. 419,303

1 Claim. (Cl. 196—52)

The present invention relates to a method of treating hydrocarbons, and in particular, it relates to a method for refining petroleum for the purpose of producing good yields of high octane number motor gasoline.

In carrying my invention into effect, I charge a crude petroleum oil to a fractionating column and I fractionate it into a plurality of separate cuts or fractions, including a light naphtha, a heavy naphtha, a wide cut gas oil, and a residuum representing approximately 20% bottoms on the total crude. Of course, the foregoing manner of fractionating the original crude petroleum oil is merely illustrative of my process and other cuts or fractions may be obtained from the original crude. In particular, the width of the naphtha cuts or fractions, that is to say the boiling range of the same, may be varied as a means of controlling the composite gasoline octane number, mean value or level, as will more fully appear hereinafter. I then subject the various fractions, except the light naphtha to separate treatments as follows: reform the heavy naphtha, catalytically crack the gas oil and coke the residuum, polymerize the unsaturates from the coking operation and then combine the products thus formed which boil in the gasoline range to recover from the process maximum quantities of high octane gasoline.

In order to afford a better understanding of my invention, reference is had to the accompanying drawings which show diagrammatically a flow plan indicating my improved method of processing a crude oil.

Referring in detail to the drawings, a crude petroleum oil is introduced into the system in line 1 and thence discharged into a furnace 3 where it is heated to a temperature of, say, about 750° F. and thence withdrawn through line 5 and discharged into the fractionating column 7. Several cuts or fractions are recovered from the fractionating column as follows: A light naphtha is withdrawn overhead through line 10 and delivered to a stabilizer 11 for blending with other gasoline produced in the process, as will more fully appear hereinafter. A heavy naphtha is withdrawn from the fractionating column 7 through line 14, discharged into a furnace 15 where it is heated to a temperature of, say, 900° F., thence withdrawn through line 16 and discharged into a catalytic fixed bed hydroforming reactor 26 containing a hydroforming catalyst, such as an alumina-chromia catalyst or other known hydroforming catalyst, where said heavy naphtha is reformed in the presence of hydrogen in a manner known

to the art. This operation is carried out preferably at a temperature within the range from about 880° F. to 980° F., at a pressure of from 100-600 lbs./sq. in. gauge, and at a feed rate of 0.3 to 2.0 volumes of liquid naphtha/reactor volume/hour. Approximately 1000-5000 cu. ft. of the butane-free gas, i. e., containing C₃, C₂, and C₁ hydrocarbons as well as hydrogen, produced in the process, per barrel of oil is recycled through line 29 for the purpose of maintaining the desired hydrogen concentration in the reaction zone.

Instead of catalytically hydroforming the naphtha, it may be reformed thermally to improve the quality of the naphtha. This may be a coil-only operation thus obviating the necessity for using reactor 26 since the reforming operation may be performed in coil 15.

The reformed naphtha is withdrawn from reactor 26 or from coil 15 through line 21 and thence discharged into a separation drum 23 from which gasoline is taken overhead through line 24 and delivered to a stabilizer 26. An aromatic low gravity polymer is withdrawn through line 30 from the bottom of the separation drum 23 and sent to fuel oil storage tank 100. The C₄ hydrocarbons produced in hydroforming are highly saturated and hence are not readily susceptible to subsequent polymerization to hydrocarbons in the gasoline boiling range. In the process here in question, hydroformed gasoline including the C₄ cut is withdrawn through line 27, the included butane being used to provide the necessary volatility in the final blend of gasoline produced from the several steps in the combination of processes. Butane-free gas from the hydroforming process is vented overhead through line 28 from the stabilizer 26, with the exception of the gas which is recycled through line 29 for the purpose of maintaining the necessary hydrogen concentration in the hydroforming reactor.

Referring back to fractionating column 7, a second cut comprising a wide boiling range gas oil is withdrawn through line 32, heated in the furnace 35 to a temperature of say 900° F., thence withdrawn through line 37 and mixed with a powdered catalyst, such as an acid treated clay, the catalyst being obtained from a supply source 40 through line 42 and dispersed or suspended in the gas oil vapors in line 37. The dispersion of catalyst in oil is then passed through a reactor where the gas oil undergoes cracking in a system represented generally by 50. The equipment for carrying out this step or stage of my process may be such as that shown, for example, in the application of Eger V. Murphree et al., Serial No.

371,923, filed December 22, 1940, or any other suitable system in which a gas oil is catalytically cracked in a continuous operation in the presence of a powdered catalyst. The cracked vapors are recovered from the catalytic cracking system through line 52 and after separation of the catalyst by a suitable device or devices, such as cyclone separators and/or Cottrell precipitators, the vapors are discharged into a fractionating column 56. High boiling cycle stock is recovered from fractionator 55 through line 62, and this oil is mixed with the bottoms from fractionating column 7 as will subsequently appear, to be discharged into a coking vessel 77. Heating oil of say 700° F. E. P. is recovered from fractionating column 55 through line 60 and delivered to a suitable storage vessel 65, to be sold as such or it may be recycled for further gasoline production if desired. Gasoline and gas are taken overhead from fractionator 55 through line 57 and delivered together with the light naphtha from line 10 to stabilizer 11. Debutanized gasoline is withdrawn through line 12 from stabilizer 11 and delivered to gasoline accumulator 101 where it is blended with gasoline from other steps in the process as will be shown hereinafter. Gases including butane are taken overhead from stabilizer 11 through line 110 and delivered to fractionator 112 from which C₃ and C₄ hydrocarbons are taken off the bottom through line 114 and lighter gas, i. e., C₁ and C₂ hydrocarbons, withdrawn overhead through line 115. The C₃ and C₄ hydrocarbons produced in catalytic cracking contain appreciable quantities of unsaturates suitable for catalytical polymerization to hydrocarbons in the gasoline boiling range, as will be shown herein-after.

Referring again to fractionator 7, residuum (about 20% to 30% of the crude) is withdrawn through line 70 and mixed with catalytic gas oil bottoms in line 62, as previously indicated, and then discharged into a furnace 75 where it is heated to a temperature of say 800° F.-900° F., whereupon the mixture is discharged through line 76 into a coking vessel 77, preferably of the down-flow type although other types may be used, where it is converted to coke, gasoline and lighter hydrocarbons. The residuum is coked in drum 77 at conditions of high temperatures and short contact or residence time within the coking zone, say 10 to 15 seconds, such as are described in the application of Walter F. Rollman, Serial No. 403,822, filed July 24, 1941, these conditions being especially suitable for the production of high yields of high octane gasoline from the residuum. The necessary high temperature, namely, say, 1000° F. to 1500° F. prevailing in coking drum 77 is obtained as the sensible heat of steam produced in furnace 75 from water in line 80 and introduced into the coking drum through line 88. Other gaseous mediums, such as ethane, methane, flue gas, etc., may be used although steam is preferred. The steam is superheated to a temperature of from 1500° F. to 1800° F. and flows countercurrently upward against the down-flowing oil through the coking drum 77. The coking drum itself is maintained preferably at a pressure of from about 0 to 150 lbs./sq. in. gauge. The more volatile products of the coking operation containing gasoline and lighter hydrocarbons are withdrawn through line 90, thence discharged into a separator 92.

From separation drum 92, a fuel oil is withdrawn from the bottom thereof through line 94 and discharged into line 30 for eventual discharge

into fuel oil receiver or accumulator 100, where it is mixed with the hydroformed polymer as mentioned above. Under certain conditions it may be desirable to return this stock to line 70 for further coking. It is pointed out that in coking drum 77 among the products obtained are gasoline and lighter hydrocarbons and a very low gravity fuel oil, with substantially no gas oil formed. Therefore, the overhead product in line 106 which leads to fractionator 98 contains, as stated, gasoline, C₄ hydrocarbons and lighter hydrocarbons, and, of course, steam. Debutanized gasoline is withdrawn from fractionator 98 through line 107 and is discharged into accumulator 101 where it is mixed with gasoline produced elsewhere in the process, as will be shown hereinafter. Water is withdrawn thru line 105. Gases produced in the coking process, including C₄ hydrocarbons, are taken overhead from fractionator 98 thru line 120 and discharged to secondary fractionator 104 from which propane-free gases are vented overhead thru line 103, and C₃ and C₄ hydrocarbons are withdrawn from the bottom of the fractionator thru line 106. The C₃ and C₄ hydrocarbons are highly unsaturated, and the C₄ cut contains material quantities of butadiene, which is recovered as such in butadiene recovery unit 125. This equipment, as is true of the other equipment described herein, is shown quite schematically in the flow plan. Butadiene is withdrawn through line 127 and collected in accumulator 129. The remaining C₃ and C₄ hydrocarbons produced in the coking process, freed of butadiene, are withdrawn from the butadiene recovery unit through line 130.

The above-mentioned butadiene-free C₃ and C₄ hydrocarbons produced in the coking process are mixed with the C₃ and C₄ hydrocarbons from the catalytic cracking process. The resulting blend thus comprises all the hydrocarbons of this type produced in the combination of processes, with the exception of the highly saturated C₄ produced in hydroforming and included in the gasoline withdrawn from that process (line 27). The mixture is discharged into furnace 131 where it is heated to a temperature suitable for catalytic polymerization and thence discharged into a polymerization unit 135 containing catalyst and operating preferably under a pressure in the neighborhood of 100 lbs./sq. in. The unsaturated hydrocarbons present in the feed to the polymer unit are thereby polymerized to hydrocarbons in the gasoline boiling range. It is understood, of course, that necessary provisions for recycling through the polymerization unit and for the withdrawal of saturated unpolymerizable hydrocarbons from the system although not shown in the schematic flow plan, are to be understood and included as part of the unit. The polymerized product is withdrawn from the polymerization unit through line 140 and delivered to gasoline storage 101 where it is mixed with other gasoline produced in the combination of processes. The gasoline in storage 101 may be further refined by treatment with acid, doctor solution, clay and the like, to give a finished gasoline. Tetraethyl lead may also be added to improve the octane number still further.

The above described combination is obviously quite flexible both as to product quality and yields, but it is contemplated that in its preferred form the combination of processes will be so adjusted that when including catalytic polymer gasoline and the saturated C₄ from the hydroformer, little if any excess C₄ is produced over 10 lbs. R. V. P.

gasoline. In other words, the gasoline produced will be essentially 10 lb. R. V. P. gasoline with no excess butane. The following yields and product quality were obtained from an East Texas crude when operating under the preferred procedure:

Gasoline (10# R. V. P.)	vol. per cent.	60.0
Heating oil (31° A. P. I.)	do	17.2
Fuel oil (8.6° A. P. I.)	do	9.4
Butane-free gas	weight per cent.	11.2
Coke	do	1.9
Butadiene	do	0.25
Gasoline—octane number (C. F. R.)		90.8

The high yield and octane number of the gasoline obtainable by this combination of processes is notable. Under other operating conditions the heating oil and fuel oil may be further processed to yield lighter products and coke.

While I have set forth certain details hereinbefore, obviously numerous modifications of my invention may be made without departing from the spirit thereof.

What I claim is:

A method for refining petroleum oil to produce high yields of high octane gasoline and substantial quantities of butadiene which comprises heating a total crude oil, discharging the heated oil

5 into a fractionation zone, recovering a light naphtha from said fractionation zone, catalytically hydroforming said heavy naphtha, recovering a gas oil from the fractionation zone, catalytically cracking said gas oil to produce catalytically cracked gasoline, C₃ and C₄ unsaturated hydrocarbons and high boiling cycle stock, recovering a heavy residual oil from said fractionation zone, mixing the high boiling cycle stock 10 recovered from the catalytic cracking zone with the heavy residual oil, coking said mixture at temperatures in the range of from about 1000° F. to 1500° F., in the presence of added steam, permitting the oil to remain in the coking zone for a period of from about 10 to 15 seconds, recovering coke still gasoline from said coking zone, 15 recovering butadiene from the C₄ hydrocarbons produced in the coking step, catalytically polymerizing unsaturated C₂ and C₄ hydrocarbons produced in the catalytic cracking step and remaining after recovery of butadiene from the C₄ hydrocarbons and blending together the light naphtha, the hydroformed naphtha, catalytically cracked gasoline, coke still gasoline, and catalytic 20 polymer.

WALTER F. ROLLMAN.
